INVENTOR.
Ferdinand J. Castillo

UNITED STATES PATENT OFFICE

157,339

BANK

Ferdinand Joseph Castillo, San Francisco, Calif.

Application March 16, 1949, Serial No. 1,430

Term of patent 14 years

(Cl. D34—11)

To all whom it may concern:

Be it known that I, Ferdinand Joseph Castillo, a citizen of the United States, resident of San Francisco, in the county of San Francisco and State of California, have invented a new, original, and ornamental Design for a Bank, of which the following is a specification, reference being had to the accompanying drawings, forming a part thereof.

Fig. 1 is a front view of a bank, showing my new design,

Fig. 2 is a side view thereof.

I claim:

The ornamental design for a bank, as shown.
FERDINAND JOSEPH CASTILLO.
